F. GRUB

GASEOUS FUEL STOVE

Filed Sept. 15, 1924

Fig. 1.

UNITED STATES PATENT OFFICE.

FRED GRUB, OF CHICAGO, ILLINOIS.

GASEOUS-FUEL STOVE.

Application filed September 15, 1924. Serial No. 737,686.

To all whom it may concern:

Be it known that I, FRED GRUB, a citizen of the United States, and a resident of Chicago, in the county of Cook and State of Illinois, have invented certain new and useful Improvements in Gaseous-Fuel Stoves, of which the following is a full, clear, and exact description.

The invention relates to gaseous fuel stoves and more particularly to those stoves which are adapted to be heated by means of fuel oil such as kerosene or gasoline.

In the use of the aforementioned type of stoves it frequently occurs that the vaporizer is not heated sufficiently before the burner is lighted so that smoke results. This smoke is obnoxious inasmuch as it pollutes the air in the room in which the stove is disposed and causes a film of carbon to be deposited 20 on the under side of the cooking receptacles which are placed above the burner.

One object of the invention is to provide a cover plate for a gaseous fuel stove burner in which provision is made for deflecting the 25 products of combustion into the chimney when the burner is first lighted.

A further object of the invention is to provide a burner or cover plate in which provision is made for heating cooking vessels 30 thereon either directly or indirectly, and whereby the maximum amount of heat generated may be utilized.

A still further object of the invention is to secure the burner vaporizer to the cover 35 plate so that the vaporizer may be removed from the stove simultaneously with the cover plate.

The invention consists in the several novel 40 features hereinafter set forth and more particularly defined by claims at the conclusion hereof.

In the drawings: Fig. 1 is a vertical section of a gaseous fuel stove provided with the new and improved cover plate for the 45 burner. Fig. 2 is a plan view of the invention, a portion being broken away to show the slots in the inner member of the cover plate. Fig. 3 is a detail section of a portion of the burner plate showing how the 50 slots in the upper and lower members may be positioned to register so as to allow the flames and heat from the burner to heat directly the cooking receptacles disposed thereon.

The invention is exemplified in a stove

of the usual construction comprising a bottom 8, a top 9, and a rear wall 10. Top 9 is provided at its rear end adjacent wall 10 with an upwardly extending annular flange 12 around which the base of a chimney 11 is secured in the usual manner. A fuel burner 14 is disposed between bottom 8 and an opening 15 in top 9 which is provided with an annular recess 16 in which the cover plate is adapted to be positioned and held. 65

The new and improved cover plate consists of an annular outer member 20 and an inner member 21 movable relatively to said outer member and pivotally secured thereto by means of a bolt and nut 22. A vaporizer and spreader for the fuel from the burner 14 is centrally disposed on the under side of the inner member above burner 14 and comprises an inner and intermediate perforated member 24 and 25 respectively, and an outer member 26 which is slotted, as at 27. These members are cylindrical and cup-shaped and are rigidly secured to inner member 21 by means of rivets 29. By securing the vaporizer to the cover plate access to the burner 80 is had immediately upon the removal of the cover, inasmuch as the cover and vaporizer are removed simultaneously. A recess 30 and a bridge 31 are formed in the margin of the outer member 20 so that a suitable tool 75 85 may be inserted in the recess for the removal of the vaporizer, as well understood in the art.

A depending annular flange 20^a is formed 90 on the under side of member 20 and marginally spaced therefrom. This flange is integrally formed and extends downwardly and outwardly. A flange 21^a is integrally formed on inner member 21 and engages and conforms to the inner periphery of flange 95 20^a. By means of these flanges the heat is accumulated on the under side of the cover so that a maximum quantity of the heat produced may be utilized.

A plurality of slots 32 extend through the outer member 20 and are concentrically and radially arranged with respect to the bolt 22, and are disposed diametrically opposite each other. A similar group of slots 33 extend through the inner member 21. The distance between the slots on each of the members respectively is slightly greater than the width of each slot so that by relative rotation of the two members the slots on each of the members may be brought into register 100 105 110

with each other and the heat produced by the burner transmitted directly to the receptacle upon the cover plate.

Slots 34 extend through flange 20^a and are disposed diametrically opposite each other and are adjacent the slots 32. A similar group of slots 35 extend through flange 21^a of the inner member and are disposed between the slots 33 of the inner member 21. 10 By means of this arrangement it will be readily seen that when the outer and inner members are rotated relatively to each other and the slots 32 and 33 brought into register, that the slots on the flanges will not be in 15 register with each other (as shown in Fig. 3), and all the heat generated by the burner will be transmitted directly to the cover plate. When the members are rotated relatively to each other so that the slots 32 and 20 33 are not in register, it will readily be seen that the slots 34 and 35 in the flanges will be in alignment so that the heat and smoke will not be transmitted through the cover plate but will pass along the top 9 of the stove 25 and into the chimney.

The cover plate is provided with means for manually moving the two members relatively to each other which comprises an arcuate slot 38 extending through the outer member 20 and a lug 39 rigidly secured to the inner member 21 and extending through said slot. Ridges 40 may be integrally formed on the outer member 20 and radially disposed with respect to the bolt 22 so that 35 cooking receptacles may be held above the cover plate in spaced relation.

The invention exemplifies a burner plate in which provision is made for deflecting the products of combustion into the chimney when the burner is first lighted, and in which provision is made for heating the receptacles held above the burner plate either directly or indirectly.

The invention is not to be understood as restricted to the details set forth, since these may be modified within the scope of the appended claims, without departing from the spirit and scope of the invention.

Having thus described the invention, what I claim and desire to secure by Letters Patent, is:

1. The combination with a stove having a combustion chamber provided with a top wall having an opening therein, an outlet stack for the products of combustion, and a burner for gaseous fuel disposed in said chamber and under said opening, of a cover for the opening in the top wall of the stove consisting of a substantially flat top member having an outwardly extending rim adapted to set upon the margin of the top wall adjacent the opening to support the cover, said top member being provided with openings to permit the products of combustion to pass therethrough directly to a vessel disposed

over the cover, and a depending member disposed inwardly of the rim and within the combustion chamber for directing the said products of combustion to said top member, said depending member having openings 70 therein for permitting the said products to pass under the top wall of the stove laterally to the stack, and means for conjointly closing the openings in the top member and for opening the openings in the depending member 75 so the products will pass directly to the stack and be prevented from passing through the top member, and for opening the openings in the top member and closing the openings in the depending member so 80 the products will pass directly through the top member of the cover to the said vessel.

2. The combination with a stove having a combustion chamber provided with a top wall having an opening therein, an outlet 85 stack for the products of combustion, and a burner for gaseous fuel disposed in said chamber and under said opening, of a removable cover for the opening in the top wall consisting of a substantially flat top 90 member having an outwardly extending rim adapted to set upon the margin of the top wall adjacent the opening to support the cover, said top member being provided with openings to permit the products of combustion to pass therethrough directly to a vessel disposed over the cover, and a depending annular member disposed inwardly of the rim and within the combustion chamber for directing the said products of combustion 100 to said top member, said annular member having openings therein for permitting the said products to pass under the top wall of the stove laterally to the stack, and rotatable means mounted on the under side 105 of the top member for conjointly closing the openings in the top member and for opening the openings in the annular member so the products will pass directly to the stack and be prevented from passing through the top member, and for opening the openings in the top member and for closing the openings in the annular member so the products will pass directly through the top member to the said vessel. 110

3. The combination with a stove having a combustion chamber provided with a top wall having an opening therein, an outlet stack for the products of combustion and a burner for gaseous fuel disposed in said chamber and under said opening, of a removable cover over the burner for the opening in the top wall and provided with openings to permit the products of combustion to pass therethrough directly to a vessel 120 disposed over the cover and with a depending member for directing the products to said cover and having openings therein for permitting said products to pass under the top wall of the stove laterally to the stack, 125

means for conjointly closing the openings in the cover and for opening the openings in said member so the products will pass directly to the stack and be prevented from passing through the cover, and for opening the openings in the cover and closing the openings in said member so the products will pass directly through the cover to the vessel, and perforated vaporizing-members in the combustion chamber and secured to the under side of the cover.

4. The combination with a stove having a combustion chamber provided with a top wall having an opening therein, an outlet stack for the products of combustion, and a burner for gaseous fuel in said chamber and under said opening, of a cover for the opening provided with an imperforate portion and openings around said portion to permit the products of combustion to pass therethrough directly to a vessel disposed

over the cover, said cover being provided with a depending member for directing said products to said cover and having openings therein for permitting the products to pass under the top wall of the stove laterally to the stack, means for conjointly closing the openings in the cover and opening the openings in said member so the products will pass directly to the stack and be prevented from passing through the cover, and for opening the openings in the cover and closing the openings in said member so the products will pass directly through the cover to the vessel, and perforated vaporizing-members in the combustion chamber extending inwardly of the openings in said cover and secured on the under side of said imperforate portion.

Signed at Chicago, Illinois this 9th day of August, 1924.

FRED GRUB.
